DESIGN FOR A DRESS

Annette L. Kulik, Chicago, Ill.

Application March 5, 1938, Serial No. 75,607

Term of patent 3½ years

To all whom it may concern:

Be it known that I, Annette L. Kulik, a citizen of the United States of America, residing in Chicago, in the county of Cook and State of Illinois, have invented a new, original, and ornamental Design for a Dress, of which the following is a specification, reference being had to the accompanying drawing forming part thereof, wherein,

I claim:

The ornamental design for a dress, substantially as shown.

ANNETTE L. KULIK.
